SELF-CONTAINED, SPEED-VARYING
COUNTERSHAFT UNIT

Paul B. Reeves, Columbus, Ind., assignor to
Reeves Pulley Company, Columbus, Ind., a cor-
poration of Indiana

Application October 24, 1949, Serial No. 123,171

5 Claims. (Cl. 74—230.17)

1

The present invention relates to a self-contained, speed-varying countershaft unit. The primary object of the invention is to provide a compact, unitary structure, entirely self contained so that it is not dependent, for its operation, upon elements with which it is to be associated, which can be manufactured and sold for immediate and unskilled installation between a machine to be driven and a power source, the unit being of such character that, when so installed, it can be operated to vary, steplessly, the speed ratio between such power source and such machine. A further object of the invention is to provide a unit of the character described in which, very inexpensively and very compactly, means is provided for stepless adjustment of that element of the unit which produces the desired speed variation.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a plan view of a unit constructed in accordance with my invention, shown in operative association with conventionally illustrated power means and driven means;

Fig. 2 is a vertical section taken substantially on the line 2, 2 of Fig. 1; and

Fig. 3 is an end elevation with parts shown in section, substantially as indicated by the line 3, 3 of Fig. 2.

Referring more particularly to the drawings, it will be seen that my unit comprises a base, indicated generally by the reference numeral 10, and including a foot 11 which is preferably provided with elongated openings 12 and 13 therethrough for the reception of means for fastening the base to a suitable bed or foundation. Standing from the foot 11, I have provided a pair of parallel side walls 14 and 15 joined or spanned by a curved top wall 16, as most clearly illustrated in Fig. 2, to define a chamber C, open at its front end, as at 17, but otherwise closed, except that said chamber may, if desired, open also through the foot 11.

Near the root of the opening 17, the base is provided with a transversely-extending bearing 18 in which is mounted a journal pin 19 which, in the illustrated embodiment of the invention,

2

projects at its opposite ends beyond said bearing to provide trunnion means for a lever 20. In the illustrated embodiment of the invention, said lever is provided at its lower end with furcations 21 and 22 which are respectively supported upon the opposite ends of the pin 19. The upper end of the lever is preferably webbed, as at 23, and, in an intermediate region, the web is preferably thickened to provide a pad area 24 for a purpose later to become apparent.

At its upper, or free, end, the lever is formed to provide a transverse bearing 25 formed with a bore 26 therethrough disposed upon an axis parallel with the axis of the pin 19; and a dual V-pulley assembly, indicated generally by the reference numeral 27, is supported upon said free end of the lever 20. This dual V-pulley assembly may preferably, but not necessarily, be constructed in accordance with the disclosure of my copending application Serial Number 94,094, filed May 19, 1949, for Multiple Expansible Pulley Unit.

As shown, it comprises a shaft 28 journaled in the bore 26 of the bearing 25 and arranged therein for axial floating movement. One end of the shaft carries a ring washer 29 or other suitable means for limiting the axial movement of said shaft in one direction by engagement with the bearing 25; while the other end of the shaft carries, outboard with respect to the bearing 25, a plurality of coned disc elements cooperating to provide a dual V-pulley. As shown, a coned disc 30 is fixed to the shaft near the bearing 25 with its coned face directed away from said bearing, and a second coned disc 31 is fixed to the shaft at its end remote from the bearing 25, with its coned face directed toward the bearing 25. Supported on the shaft 28 for axial floating movement relative thereto, and between the discs 30 and 31, is a double coned disc element 32 having one coned face 33 presented toward the coned face of the disc 30 and an opposite coned face 35 presented toward the disc 31. The disc 32 thus cooperates with the disc 30 to provide a variable-effective-diameter V-pulley frictionally receiving an edge-active belt 34; and cooperates with the disc 31 to provide a variable-effective-diameter V-pulley frictionally engaging an edge-active belt 36. Obviously, when the parts are in the positions illustrated in the drawings, the effective diameter of the pulley engaging the belt 34 is a maximum, while the effective diameter of the pulley engaging the belt 36 is a minimum. Movement of the disc 32 toward the right as viewed in Fig. 3 will decrease the effective diameter of the

former and will correspondingly increase the effective diameter of the latter.

A coiled spring 37 is disposed in the chamber C, one end thereof being anchored upon a pin 38 projecting into said chamber through a perforation 39. Said spring projects through the opening 17, and its opposite end is anchored upon a pin 41 which, in the illustrated embodiment of the invention, spans said opening and has its opposite ends lodged in sockets 42 and 43 formed in the forward or outer face of the lever 20. The effect of the spring 37, thus, is to urge the lever 20 toward its illustrated position in which the pad 24 engages an abutment 44 provided at the upper end of the base 18.

A threaded bore 45 is formed in the abutment 44 upon an axis transverse to the axis of the pin 19 but in a horizontal plane above the horizontal plane containing the axis of said journal pin. A screw 46 is threadedly mounted in said bore 45, and is provided, at one end, with a rounded nose 47 adapted to engage the pad 24 of the lever 20. A hand wheel 48 is fixed to the opposite end of said screw to facilitate rotation thereof; and preferably a pair of nuts 49 will be mounted on said screw to act as stop means to limit the degree of adjustment of said screw toward the right as viewed in Fig. 2.

It will be seen that rotation of the hand wheel 48 in one direction will shift the screw 46 toward the right to force the lever 20 to swing, against the tendency of the spring 37, in a clockwise direction; while rotation of the hand wheel 48 in the opposite direction will retract said screw, permitting the spring 37 to return the lever 20 toward, and ultimately into, engagement with the abutment 44. Said abutment limits counterclockwise swing of the lever 20, while the nuts 49 adjustably limit clockwise swing of said lever. It will also be perceived that the speed-varying unit thus described is completely self-contained, and that all operative adjustments thereof are entirely independent of any device with which such unit may be associated for operation.

The unit of the present invention is intended to be mounted between a power source and a machine to be driven, to transmit power from said source, within infinite speed variation within its range, to the driven element. As shown in Fig. 1, the unit is so mounted between a power source such as a motor 51 and a unit such as a shaft 53 to be driven. The belt 34 is trained over a pulley 50 on the motor spindle, while the belt 36 is trained over a pulley 52 on the shaft 53. It will be seen that the median planes of the V-pulleys 50 and 52 are slightly offset from each other so that the belts 34 and 36 will be straight when the power transmission unit is properly located.

The position of the transmission unit, relative to the motor spindle and the shaft 53, and the lengths of the belts 34 and 36 will preferably be such that, when the pad 24 is in contact with the abutment 44, the disc 32 will be in its illustrated position, so that the effective diameter of the variable pulley engaging the belt 34 will be a maximum, and the effective diameter of the variable pulley engaging the belt 36 will be a minimum. Now, if the motor 51 is energized, the shaft 53 will be driven at a speed less than that of the motor pulley 50.

If, now, during operation of the assembly, the hand wheel 48 is rotated to shift the screw 46 toward the right, the screw nose 47 will engage the pad 24 to swing the shaft in a clockwise direction. Thereby, the belt 34 will be pulled more

deeply into the V groove between the discs 30 and 32 to shift the disc 32 toward the right as viewed in Fig. 3. Concurrently, such movement of the lever 20 will reduce the distance between the shaft 28 and the shaft 53, thereby permitting the moving disc 32 to squeeze the belt 36 outwardly between the discs 32 and 31. Thus, the effective diameter of the pulley engaging the belt 34 will be steplessly reduced, while the effective diameter of the pulley engaging the belt 36 will be steplessly increased, to increase the speed of the shaft 53. As the lever is so moved, the shaft 28 will drift toward the left, relative to the bearing 25, as viewed in Fig. 3, to maintain the alignment of the belts 34 and 36.

Obviously, if the hand wheel 48 is now rotated in the opposite direction to retract the screw 46, the spring 37 will swing the lever 20 in a counter-clockwise direction, thus forcing the belt 36 more deeply between the discs 31 and 32, forcing the disc 32 to move toward the left as viewed in Fig. 3 to squeeze the belt 34 outwardly between the discs 32 and 30, and the shaft 28 will drift toward the right to maintain belt alignment.

I claim as my invention:

1. A self-contained speed-varying power transmission countershaft unit comprising a base including walls defining a chamber, journal means provided on said base near an end of said chamber, a lever oscillably mounted on said journal means and projecting away from said base, a dual V-pulley assembly supported at the free end of said lever, a spring substantially housed within said chamber and operatively engaging said lever and said base to restrain said lever resiliently against movement in one direction about the axis of said journal means, said base being provided with a threaded bore whose axis is remote from said journal means and transversely disposed relative to the axis of said journal means, and a screw threadedly mounted in said bore and engageable with said lever to swing the same in opposition to the resistance of said spring.

2. A self-contained speed-varying power transmission countershaft unit comprising a base including foot means and wall means upstanding from said foot means and providing abutment means remote from said foot means, journal means adjacent said foot means near one end thereof, lever means oscillably supported on said journal means and projecting toward said abutment means, a dual V-pulley assembly supported at the free end of said lever beyond said abutment means, a coiled spring having one end anchored on said base near the other end of said foot means and having its other end anchored on said lever at a point removed from said journal means toward said abutment means, said spring resiliently tending to hold said lever in contact with said abutment means, said base being provided with a threaded bore whose axis is remote from said journal means and transversely disposed relative to the axis of said journal means, and a screw threadedly mounted in said bore and engageable with said lever to swing the same in opposition to the resistance of said spring.

3. A self-contained speed-varying power transmission countershaft unit comprising a housing including a pair of upstanding, longitudinally-extending walls and a top wall joining said first-named walls to define a chamber having an opening at one end, transversely extending trunnion means carried on said base adjacent the bottom of said opening, lever means oscillably supported on said trunnion means, a coiled spring having

one end anchored within said chamber, extending through said opening, and having its other end anchored on said lever means intermediate the ends thereof, a dual V-pulley assembly supported at the free end of said lever, abutment means provided by said housing above said opening, and screw means located upon an axis disposed in the plane of oscillation of said lever means and operatively engaging said housing and said lever means, said spring resiliently urging said lever means toward engagement with said abutment means and said screw means being operable to swing said lever means in opposition to the tendency of said spring.

4. The unit of claim 3 in which said screw means is threadedly mounted in a threaded bore in said housing and has a one-way push engagement with said lever means.

5. The unit of claim 3 in which said V-pulley assembly comprises a shaft journaled in said lever means upon an axis parallel with the axis of said trunnion means, a coned disc fixed to said shaft, a second coned disc fixed to said shaft

10
